REVOLVING TRUNK

Julius Ritter, Jr., Racine, Wis., assignor to
Hartmann Trunk Company, Racine, Wis., a
corporation of Wisconsin

Application March 23, 1936, Serial No. 70,230

1 Claim. (Cl. 248—129)

The present invention relates in general to improvements in revolving trunks, and relates more specifically to an improved mounting for rotatably supporting a trunk or other type of container so as to permit turning movement thereof for convenient access to the doors or closure members for access to the interior of the container.

Heretofore several different forms of rotary supports for trunks have been provided. In one instance the support consisted of a circular bottom member adapted to rest upon the floor and carrying a metallic lower bearing plate provided with a central hub which coacted with a bore in a rotary upper plate secured to the lower end wall of the trunk, and ball bearings were interposed between these upper and lower relatively rotatable plates. This form of construction had certain disadvantages including the necessity for a space between said plates for the accommodation of the ball bearings whereby the supporting structure was too high and interfered with the stability of the supported trunk.

Some of the objections were overcome by another structure wherein a series of rollers were attached directly to the lower wall of the trunk and were revoluble therewith to coact with the upper surface of a base plate. This construction was less heavy and bulky than the first-mentioned construction and permitted the base plate to be disposed closer to the wall of the trunk. However, the base of the trunk was still elevated somewhat and the structure had objections so far as stability was concerned.

It is the primary object of the present invention to provide a rotary support for a revolving trunk in which antifriction devices are interposed between a lower plate and a plate in the bottom of the trunk, affixed to one of said members and are embedded in recesses therein to coact with the surface of the other of said members, whereby the rotary support is extremely compact and the load is lowered, greatly enhancing the stability of the entire structure.

Another object of the invention is the provision of a rotary support wherein the vertical height of the supporting structure is decreased, without any sacrifice in the thickness of the plate which rides on the anti-friction devices.

Still another object of the invention is to provide a rotary support for revolving trunks wherein rollers are utilized and the same are mounted in and affixed to the lower plate and contact the surface of an upper plate, the trunk being maintained centrally of the lower plate by a simple

pivot bolt which is readily exteriorly accessible and makes for ease in the assembly of the device.

The lower ends of trunks are usually provided with supporting feet or projections, and in the present invention said feet are cupped and depend from the lower plate and cooperate in the provision of means for the reception of antifriction members on which the trunk turns, whereby space is saved, height is minimized, and the thickness of the bearing and turning members is not affected.

A clear conception of an embodiment of the invention, and of the mode of constructing and of utilizing revolving trunk structures built in accordance with the improvement, may be had by referring to the drawing accompanying and forming a part of this specification in which like reference characters designate the same or similar parts in the several views.

Fig. 1 is a top view of a standard two compartment trunk having the improved mounting applied thereto, the compartment doors or closures being shown in closed position in full lines, and in partially open positions in broken lines;

Fig. 2 is an enlarged fragmentary vertical sectional view of the lower portion of the trunk and mounting, taken along the line 2—2 of Fig. 1;

Fig. 3 is a bottom view of the trunk and its mounting;

Fig. 4 is an enlarged view of the lower plate member removed from the trunk and looking at the inner or top face thereof; and

Fig. 5 is an enlarged, detail, sectional view taken on line 5—5 of Fig. 4.

While the invention has been illustrated herein as being specifically applied to a standard two compartment trunk, it is not intended to limit the scope by such specific disclosure, and some of the novel features may obviously be more generally applicable.

The container or trunk comprises in general a box-like structure consisting of side walls 6, a sectional top 7, a bottom member 8, a central vertical partition 9 dividing the trunk into oppositely disposed compartments, and doors or closures 10 for permitting access to the several compartments. The fixed section of the top may be provided with a handle 11, and each of the closures 10 is hingedly attached to the adjacent side wall 6 and is provided with one or more latches 12 cooperable with the other side wall 6 to maintain the closure in closed position.

The bottom member 8 is formed of heavy fiber, or its lower face is covered with fiber, and near

its outer edges it is thickened by a depending portion 12 which has an inner circular periphery 13 to define a circular recess 14. A circular base or lower supporting plate 15 is revolvably disposed within the recess 14 and is held in accurately spaced relation to the member 8, by a bolt 16. The lower head of the bolt coacts with the lower face of the plate 15, and said bolt has a reduced upper threaded end forming a shoulder 17 coacting with a washer 18 secured to the center of the trunk base 8. The shoulder 17 of the bolt 16 may be pulled into snug engagement with the washer 18 by a nut 19 coacting with the threaded bolt end and with a washer 20, and a lock washer 21 may be inserted between the washer 20 and the nut 19. A cotter pin 22 may also be utilized to prevent release of the nut 19, thus insuring rigid attachment of the bolt 16 to the trunk.

For the support of the trunk, the lower face 20 of the plate 15 has depending therefrom a plurality of spaced, cupped, supporting feet 23. The cupped portions of these feet 23 register with recesses 24 in the member 15. In each recess 24 there is disposed a roller bearing 25 which is 25 rotatably mounted in a bracket 26 extending into and straddling a recess 24. The flange portions of a bracket 26 are secured to the plate 15 by pins 27 which also pass through the flanges of a foot 23 and also serve as the securing means therefor. As shown best in Fig. 5, the major portion of a roller bearing 25 is confined within a recess 24, but said roller bearing projects slightly above the top surface of the member 15 and engages the lower face of the trunk bottom 8, 35 which rides on said bearings. The space between the members 8 and 15 is, however, minimized.

When the trunk is resting upon the base plate 15 through the intermediary rollers 25, the entire assemblage may be slid along the floor, the feet 40 23 taking the wear while the trunk proper is elevated from the floor sufficiently to prevent damaging thereof. If it is desired to obtain access

to either of the trunk compartments, this may be done from any point around the trunk, by merely rotating the same upon the base plate 15 and about the central axis of the pivot bolt 16. As the trunk is rotated, the lower face of the 5 bottom member 8 rides on the turnable rollers 25 mounted within the base plate. The rotatable support is compact because the lower plate 15 seats within the recess 14, and because of the recessed mountings for the rollers 25, there is 10 little clearance between the adjacent faces of the members 8 and 15. The entire assembly is rendered very stable and tipping tendency is resisted by said low and compact mounting. The structure is simple and is easy to assemble, and 15 parts thereof are accessible. The roller bearings contact the member 8 in a line, and wear is minimized. The improved construction presents a neat appearance, can be applied to any standard 20 wardrobe trunk, and has proven highly satisfactory in use.

It should be understood that it is not desired to limit the invention to the exact details of construction herein shown and described, for various modifications within the scope of the claim may 25 occur to persons skilled in the art.

What is claimed as the invention is:—

In a rotatable trunk having a rigid, integral bottom member, a base plate below said bottom member, said base plate being formed, inwardly 30 of the surface adjacent the bottom, with a plurality of spaced, individual recesses, bearing brackets extending into said recesses, roller bearings journaled in said brackets within said recesses and coacting directly with a surface of said 35 bottom, a supporting foot depending from the under side of the plate below each recess, common means for securing each bracket and foot thereadjacent directly to said plate, and a pivot bolt directly connecting said plate and said trunk 40 bottom member.
